(57) **CLAIM**

The ornamental design for a trolling bait holder, as shown and described.

DESCRIPTION

1. Trolling bait holder

1.1 : Left

1.2 : Top

1.3 : Right

1.4 : Bottom

1.5 : Back

1.6 : Front

1.7 : Unfolded

A holder for use in holding trolling bait prior to use of the bait in trolling; a rod passes through the eye sockets of the bait, which are empty, and which bait are individually releasable from the handle as bait is needed.

The broken line showing of 5 bait fish in figure 1.1 is included for the purpose of illustrating environment and forms no part of the claimed design.
